UNITED STATES PATENT OFFICE.

GEORGE KERN, OF PERU, ILLINOIS.

DESIGN FOR A CASING FOR VENDING-MACHINES.

50,699.

Specification for Design.

Patented May 1, 1917.

Application filed February 1, 1917. Serial No. 146,036. Term of patent 7 years.

To all whom it may concern:

Be it known that I, GEORGE KERN, an alien, former subject of the Emperor of Germany, (who has declared his intention to become a citizen of the United States,) and resident of Peru, in the county of La Salle and State of Illinois, have invented a new, original, and ornamental Design for a Casing for Vending-Machines, of which the following is a specification, reference being

had to the accompanying drawings, forming a part thereof.

In these drawings, Figure 1 is a side elevation of the casing for a vending machine, and Fig. 2 is a plan of the same.

I claim:

The ornamental design for a casing for vending machines, as shown.

GEORGE KERN
